UNITED STATES PATENT OFFICE.

JOHANNES FERDINAND THIESSEN AND EMIL BECKER, OF NEUMÜNSTER, GERMANY.

SAFETY DEVICE FOR PITMEN.

No. 912,046.

Specification of Letters Patent.

Patented Feb. 9, 1909.

Application filed July 27, 1908. Serial No. 445,543.

To all whom it may concern:

Be it known that we, JOHANNES FERDINAND THIESSEN, of 21 Mühlenhof, Neumünster i. H., Germany, engineer, and EMIL BECKER, of 32 Grossflecken, Neumünster i. H., Germany, engineer, both subjects of the King of Prussia, have invented certain new and useful Improvements in Safety Devices for Pitmen.

- 10 It has already been proposed to provide intentionally points of weakness in parts of machinery with the object of insuring that the said parts shall break at these points in case of overload.
- 15 Now the present invention has for its object to provide an improved construction of such intentional points of weakness, and it consists in forming the part to be intentionally weakened, of two pieces connected together by a point allowing of relative rotary movement between the said two pieces, in providing a further connection between the said two pieces of such strength and nature that so long as there is no overload relative 20 rotary motion between the two pieces will be prevented by the said further connection, and the said two pieces will operate as one rigid part. On the occurrence of overload however, the said further connection will 25 give way and allow of relative rotary movement between the two pieces whereby the part composed of the said two pieces will become shorter or longer as the case may be, and relieve the strain produced upon said 30 part of the overload.

The drawing illustrates by way of example the application of this invention to an eccentric (designed for a crusher or breaker) shown in side elevation partly in section.

- 40 *a*, is the shaft on which the eccentric sheave *b*, is mounted.
c, is the eccentric strap connected by means of a pin, *d*, with the eccentric rod part, *e*.
- 45 *f*, is the pin in the rod, *e*, for connection to the part (not shown) to be operated.

The rod part, *e*, is substantially of U-shape in cross section and its two sides embrace the lower half of the strap, *c*. This 50 lower half is formed with a transverse bearing flange *g*, upon which fits a similar bearing surface, *h*, formed on the rod part, *e*.

The two flanges *g*, and *h*, are held against each other by a nutted bolt, *i*. The strength of this bolt is made such that it will withstand the strain of normal load. If however through overload, the strain exceeds the normal strain, the bolt, *i*, will break, and then the rod part *e* will rotate relatively to the eccentric strap until the points 60 *a*, *d* and *f* are in one and the same straight line, the flanges *g* and *h* moving apart from each other.

As the sum of the distances from *a* to *d*, and from *d* to *f* is greater than the distance from *a* to *f*, when the parts are in their working positions, the eccentric will become so much longer by the breaking of the bolt *i* that all excessive strain will cease.

In the same manner this invention may 70 be applied to an eccentric rod acting as a part in compression, with the difference that in case of breakage of the safety device, the eccentric will become shorter instead of longer.

Having thus described our invention what we claim is new and desire to secure by Letters Patent is:—

1. In a machine, the combination of two pivotally connected members, said members 80 having also outer pivot points means of predetermined strength for holding said members against pivotal movement, said members being so constructed that on the breakage of said holding means the distance between the outer pivot points of said members will be varied to relieve the strain on the machine.

2. In a machine, the combination of two members connected to rotate relatively to each other, said members having outer pivot points breakable means of predetermined strength for holding said members against rotation under normal conditions, and means whereby the distance between the outer pivot 95 points of said members is varied on the release thereof to relieve undue strain.

3. In a machine, the combination of a shaft carrying member, said members having outer pivot points a movable member 100 pivotally connected with said shaft carrying member and having a pin mounted therein, means of a predetermined strength for holding said movable member against

rotation under normal conditions, said movable member being constructed to move on the breakage of said holding means to vary the distance between the outer pivot 5 points of said members to relieve the strain on the machine.

In testimony whereof we have hereunto

set our hands in presence of two subscribing witnesses.

JOHANNES FERDINAND THIESSEN.
EMIL BECKER.
